UNITED STATES PATENT OFFICE.

JOHN L. WEAVER, OF PHILADELPHIA, PENNSYLVANIA.

PORABLE WOODWORKING MACHINE.

Application filed August 25, 1925. Serial No. 52,279.

My invention relates to portable wood-working machines, and its objects are to provide a wood-working machine of simple and strong construction which may be easily wheeled from place to place; with which the lumber used for building purposes may be quickly cut on a band saw, circular saw or a planer to an accurate fit.

These objects, and other advantageous ends which will be described hereinafter, I attain in the following manner, reference being had to the accompanying drawings in which

Figure 1 is a side elevation of a portable wood-working machine constructed in accordance with my invention,

Figure 2 a front view of the machine shown in Figure 1, looking in the direction of the arrow, certain of the parts being shown in section for clearness of illustration,

Figure 3 a plan view of the machine shown in Figure 1,

Figure 4 a fragmentary side view similar to Figure 1 showing the parts arranged for planing,

Figure 5 an enlarged section on line 5-5 of Figure 1,

Figure 6 an enlarged section on line 6-6 of Figure 1, and

Figure 7 an enlarged section on line 7-7 of Figure 2.

Referring to the drawings, 1 indicates a frame which is made up of angle bars 2 and tie plates 3 connected to form a box-shape base having a platform 4 on which an internal combustion engine 5 or an electric motor is mounted. The frame is wheeled on a pair of wheels 6 having stud shafts 7 rotatable in bearings 8 secured to the angle bars 2 of the frame. The frame is supported in wood-working position by a pair of pivoted legs 9 held in fixed position by braces 10 pivoted to the legs and detachably connected with the frame at 11. A handle 12 is pivoted to the frame so that it may be swung out of the way, as shown in dot-and-dash lines in Figure 1, when the frame is in wood-working position, and is held in wheeling position by a pair of braces 13 pivoted to the handle and detachably connected with the frame at 14.

A pair of the angle bars 2 of the frame is preferably secured diagonally to provide a support for bearings 15 in which a drive

shaft 16 is rotatably mounted. This drive shaft carries a fixed pulley 17 and a loosely mounted pulley 18 which may be operatively connected with a belt 19, connected with engine 5, by belt shifting mechanism. The belt shifting mechanism consists of a pair of opposed belt pushers 20 fixed to a slidable rod 21 connected with a lever 22 pivoted on the frame at 23.

A large belt pulley 24 fixed with the loosely mounted pulley 18 rotates with it about drive shaft 16. This pulley transmits its movement through a belt 25 to a small pulley 26 on a jointer shaft 27 rotatable in suitable bearings 28 fixed to the frame. The jointer shaft is connected with the large pulley 24 by tightening belt 25. Belt 25 is placed under tension and released by an idler pulley 29 rotatable in hangers 30 swingably mounted on the frame at 31. Tension may be placed on the belt by swinging the idler pulley against the belt by a handle 32 notched at 33 for engaging the edge 34 of a slotted member on the frame to hold the pulley in position against the belt. The tension on the belt may be released by swinging the pulley away from the belt.

A jointer head 35 is secured to the shaft between bearings 28, and a circular saw 36 is removably secured to the end of the shaft outside the left bearing 28. A jointer table 37 consists of a rear part 38, mounted on the frame for vertical adjustment by links 39 secured by bolts 40, and a front part 41 mounted on the frame for adjustment by links 42 and an adjusting screw 43. The adjusting screw is swiveled to the front table part 41 at 44 and to the frame at 45. By turning screw 43, the front table part 41 may be elevated by links 42. A circular saw table 46 has one end pivoted to the rear jointer table part 38 at 47 and the other end normally resting on the front jointer table part 41. The circular saw table is adjusted vertically by a screw 48 threaded in the part 41, and has a slit 49 through which the saw 36 extends. A dovetail groove 50 in the top of table 46 receives a tenon 51 of a lumber guide 52 so that it may be adjusted relatively to the circular saw 36. The guide is held in adjusted position by a screw 53 threaded in tenon 51, by screwing its end into binding engagement with the bottom of the dovetail groove.

Drive shaft 16 carries a band saw pulley

54 which drives a band saw 55 passing over it and a second pulley 56 mounted above the frame. Pulley 56 is rotatably mounted on a bearing in the form of a stud shaft 57 integral with a sleeve 58 adjustable on an upright tubular guide 59 fixed to an extension 60 on the frame. Extension 60 is in the form of a channel secured to and forming a part of the frame made of the angle bars 2 10 and plates 3. Sleeve 58 has a pin 61 fixed thereto and passing through a slot 62 in guide 59. The sleeve is adjusted vertically by a screw 63, threaded in extension 60, and is yieldably held in adjusted position by a 15 spring 64 mounted between screw 63 and pin 61. Suitable disks 65 are attached to each end of the spring to provide efficient bearing ends on the spring.

A band saw table 66 has an opening 67 20 through which band saw 55 passes. The table is tiltably mounted on a frame member 67 and held in position by a single bolt 68 passing through member 67 and a pair of lugs 69 disposed at opposite sides of the 25 member 67. Table 66 is normally level with the circular saw table 46 and adjacent thereto so that either table serves as an extension for the other.

The machine above set forth may be easily 30 wheeled from place to place by simply swinging the legs 9 out of the way as shown in dot-and-dash line position at 70 in Figure 1 and balancing the machine with the handle 12. The machine is set in wood-working position by swinging the legs 9 to the 35 full line position and the handle 12 to the dot-and-dash line position shown in Figure 1. The lumber may then be cut on the band saw 55 or circular saw 36. When it is desired to plane the lumber, the circular saw table 46 is removed from the jointer table 37 by removing the pivot bolts 47. The jointer table will then be as shown in Figure 4 and the lumber may be readily planed by passing 45 it over the jointer head 35.

To operate the jointer or circular saw, belt 19 is shifted onto pulley 18 by operating the lever 22 and its associated parts, to rotate the pulley 24. To connect this pulley 50 with the pulley 26 on the jointer shaft, the idler pulley 29 is swung against the belt 25 by handle 32 until one of the notches 33 fits over edge 34 on the slotted member on the frame. The tension placed on the belt will 55 cause it to rotate with pulley 24 and thus transmit movement to jointer shaft 27. The circular saw and jointer head are stopped by swinging idler pulley 29 from belt 25 to release the tension on the belt.

60 To operate the band saw, belt 19 is shifted onto the pulley 17 by operating lever 22 and the parts connected therewith. Pulley 19, being fixed on drive shaft 16, will rotate the same and the band saw pulley 54 around 65 which the band saw passes. Any desired

tension may be placed on the band saw by adjusting the screw 63 against spring 64.

The band saw table may be adjusted to any tilted position and held in that position by loosening bolt 68, tilting the table and 70 tightening the bolt again. The height of circular saw table 46 may be adjusted by turning the screw 38 and the depth of cut to be planed by jointer head 35 may be regulated by adjusting the front part 41 of the planer table by the screw 43 which causes the part 41 to be elevated or lowered by the swinging of links 42.

It will be seen that with a portable wood-working machine as above set forth, lumber used in building construction may be quickly cut to fit, and the machine may be easily transported from place to place.

While I have described my invention as taking a particular form, it will be understood that the various parts may be changed without departing from the spirit thereof, and hence I do not limit myself to the precise construction set forth, but consider that I am at liberty to make such changes and 90 alterations as fairly come within the scope of the appended claims.

Having thus described my invention, what I claim as new and desire to secure by Letters Patent is:—

1. In a portable wood working machine, a frame, a band saw table pivotally mounted on the frame, a band saw pulley rotatable above the table, a drive shaft rotatable in the frame, a second band saw pulley fixed on the drive shaft, a band saw on the pulleys, means for maintaining tension on the band saw, a jointer table pivotally mounted on the frame, a tool shaft rotatable in the frame, a jointer head fixed on the tool shaft and extending through the jointer table, a circular saw table mounted on the jointer table and pivotally connected thereto, the top of the band saw table being flush with and adjoining the top of the circular saw table, a circular saw detachably mounted on the tool shaft and extending through the circular saw table, a fixed driven pulley on the tool shaft, a loose drive pulley on the drive shaft, a belt connecting the drive and driven pulleys, means to put tension on the belt, a loose driven pulley rotatable on the drive shaft and fixed to the loose drive pulley, a driven pulley fixed on the drive shaft, a power unit on the frame, a drive belt connecting the power unit and the driven pulleys on the drive shaft, means to shift the drive belt from one pulley to the other, means to adjust the heights of the tables, and means for moving the machine from place to place.

2. In a portable wood-working machine, a frame; a jointer shaft rotatable on the frame; a jointer head carried by the shaft; a circular saw carried by the shaft; a jointer

table adjustably mounted above the jointer head; a circular saw table adjustably mounted on the jointer table; a drive shaft rotatable on the frame beneath the table; a band saw pulley carried by the drive shaft; a second band saw pulley rotatable on the frame above the tables; a band saw on the

pulleys, and a band saw table mounted on the frame adjacent to and even with the circular saw table whereby either table serves 10 as an extension of the other.

In testimony whereof I have signed my name to this specification.

JOHN L. WEAVER.
